UNITED STATES PATENT OFFICE.

WILLIAM S. BRUMMETT AND EDWARD C. REED, OF PAWHUSKA, OKLAHOMA.

KEY-ANCHOR.

1,347,773.

Specification of Letters Patent.

Patented July 27, 1920.

Application filed November 28, 1919. Serial No. 341,077.

To all whom it may concern:

Be it known that we, WILLIAM S. BRUMMETT and EDWARD C. REED, citizens of the United States, residing at Pawhuska, in the county of Osage and State of Oklahoma, have invented certain new and useful Improvements in Key-Anchors, of which the following is a specification.

Our invention relates to key anchors especially adapted for use in wooden constructions.

Among contractors and companies operating in oil fields, the foundations of drilling rigs are keyed together with wooden keys, and the continual jarring, caused by the spudding and drilling, works the keys loose, thus requiring a great deal of time and extra labor in redriving them.

Our object is to provide a device of simple, durable, and inexpensive construction, which will coöperate with the keys, when driven up, to securely anchor them in their operative positions, thereby saving the extra labor and expense of redriving above referred to, while at the same time providing for the rig a more constantly rigid foundation.

Minor objects will appear in the subjoined description.

30 A leading feature of the invention consists of a plate or other comparatively thin piece of metal provided with holes and adapted to be received between the face of the key and the piece of timber that is to be held in position thereby.

The invention consists in certain novel features of construction and arrangement of parts, as will be hereinafter described and claimed, reference being had to the accompanying drawings, in which—

Figure 1 is a broken perspective showing two pieces of timber keyed together according to the principles of my invention.

Fig. 2 is a side elevation of one form of my improved key anchor. Fig. 3 is a sectional view, taken on the line 3—3 of Fig. 2, with the additional showing of a rod as employed for distorting the holes in the anchor plate; and, Fig. 4 is a broken sectional view, on an enlarged scale, similar to Fig. 3, but showing the outwardly bent portions of the plate filed to chisel edges at opposite sides of one of the openings.

The numeral 1 indicates a flat metallic

plate formed preferably of steel, and made 55 thicker or thinner according to the size and hardness of the timbers with which it is to be used. This plate is shown in Fig. 2, as provided with an upper row of openings 2, and a lower parallel row 3. The holes 2 60 and 3 may be exactly alike to start with, but at opposite sides of the former, the metal is bent laterally outward toward one side of the plate at one side of each hole and toward the other side of the plate at the other side of the hole, to form the burs 4; whereas the holes 3 are simply plain holes in a flat or even surface.

A very easy, convenient, and rapid way 70 of forming the burs 4, is to take a rod 5, of a size adapted to be easily received into the openings, and having passed the same into an opening, force it downwardly at one end bringing it to a sharp incline relatively to the plate, in the direction of the longitudinal extent thereof, as illustrated in Fig. 3.

If a round file be passed into the openings 2, and the inner corners 6 of the burs 4 filed off, till the cutting face of the file 80 comes to the position indicated by the dotted lines 7—7 in Fig. 3, the burs will then be provided with chisel edges 8, as illustrated at one of the openings in Fig. 4.

In operation, the key anchor 1 is placed 85 between the key and the piece of timber to be held in place thereby, and then the key is driven home. On the side of the plate or anchor next the key, the burs 4 at the margins of the openings 2 will become pressed 90 into the key and firmly embedded therein, while the burs on the other side of the plate will become equally embedded in the piece of timber, so that the anchor locks the two pieces, (between which it is held), together. 95 The compressed wood on the two sides of the plate will soon swell and expand into the openings 3, which will also serve the same purpose of holding the key securely anchored in its operative position.

It will be noticed that the burs 4 on one side of the plate 1, all point in the same direction, and that those on the opposite side of the plate all point in the opposite direction, to permit the wedge to move on the 105 plate in the direction the burs next to it point; and likewise to permit the plate, if need be, to move on the piece of timber with

the least possible resistance, as the wedge is being driven up.

However, it is apparent that, in any event, the burs 4, at the margins of the openings 2, 5 will have some tendency to bruise and abrade the two pieces of wood between which the plate is held, but such will not be appreciably the case with the openings 3. The openings 2 with their burred margins will 10 at once anchor the key as soon as it is driven home, and will hold the parts firmly locked together till the wood has time to expand and swell into the openings 3, which will eventually become filled with wood that 15 does not have its grain broken. With this idea in mind, it will be noticed that the series of openings 2 are out of alinement with the openings 3, and that there are fewer of the openings 2 than of the openings 3.

20 Our anchor plate may have both kinds of openings, as illustrated in Fig. 2, or it may have only the burred openings 2, or only the plain openings 3.

When the device is provided with the 25 burred openings 2, not many of them will be required, because they take such a prompt and firm hold upon the wood: and the openings may be placed out of alinement with each other to prevent any two of them from 30 abrading the wood on the same line, as the key is being driven in. On the other hand, if the anchor be only provided with the openings 3, it makes little difference how 35 great a number of them are employed, because they have such a slight tendency to abrade the wood as the wedge is being driven home: also it makes little difference

whether they are in alinement or out of alinement with each other.

From the foregoing, it will be seen that 40 we have provided a key anchor of great simplicity and adaptability to the work required of such a device, and one that is extremely easy and economical of construction, and withal very durable. 45

Of course, it is understood that our device may be used for many other purposes besides in connection with the foundations of drilling rigs, but we have spoken of that use of it in this application, because that 50 happens to be the particular purpose for which we propose to employ it at the present time.

Having now described our invention, what we claim as new and desire to secure by 55 Letters Patent is:—

1. A device of the character described, comprising a plate having openings with oppositely extending burs at diametrically opposite sides of said openings, said plate 60 also having other plain openings, in the even surface thereof, without burs at their margins.

2. A device of the character described, comprising a plate having openings with 65 oppositely extending burs at diametrically opposite sides of said openings, said plate also having other plain openings without burs at their sides and out of longitudinal alinement with said burred openings. 70

In testimony whereof we affix our signatures.

WILLIAM S. BRUMMETT.
EDWARD C. REED.
